UNITED STATES PATENT OFFICE.

PAUL A. JONES, OF JACKSONVILLE, ILLINOIS.

HAND COVERING.

Application filed February 10, 1926. Serial No. 87,340.

This invention relates to hand coverings, more particularly to gloves of the fabric type employed by mechanics, machinists, farmers, laborers, etc., and has for its object 5 to provide, in a manner as hereinafter set forth, an article of such class formed with a reinforced gripping face thereby materially increasing the life of the article when shucking corn, and when handling metal, 10 lumber, freight, brick, etc., as well as further providing for a non-slip grip when the article is used when shucking, lifting and transporting.

A further object of the invention is to 15 provide, in a manner as hereinafter set forth, an article of the class referred to having vulcanized to its gripping surface a reinforcement consisting of a strip, length or sheet of rubber.

20 Further objects of the invention, are to provide, in a manner as hereinafter set forth, a hand covering for the purpose referred to, which is simple in its construction and arrangement, strong, durable, 25 thoroughly efficient when used and comparatively inexpensive to manufacture.

With the foregoing and other objects the invention consists of the novel construction, combination and arrangement of parts as 30 hereinafter more specifically described and illustrated in the accompanying drawings, wherein is shown an embodiment of the invention, but it is to be understood that changes, variations and modifications can be 35 resorted to which fall within the scope of the claims hereunto appended.

In the drawings wherein like reference characters denote corresponding parts throughout the several views:—

40 Figure 1 is an elevation of a hand covering, in accordance with this invention, looking towards the gripping face thereof, and the covering illustrated as a glove of the fabric type.

45 Figure 2 is a section on line 2—2, Figure 1.

Referring to the drawing the glove shown is formed throughout of fabric and generally indicated by the reference character 16 50 and comprises a body portion 17, finger stalls 18, 19, 20 and 21, a thumb stall 22, and a wrist band 23.

Vulcanized to the gripping surfaces of the 55 stalls 18, 19, 20 and 21 are respectively flat reinforcing members referred to generally

by the reference characters 24, 25, 26 and 27 and each of said members consists of two spaced sections 28, 29. Each of the reinforcing members is of a length, when vulcanized to its associated stall, to extend from 60 a point in proximity to the outer end of the stall to and slightly upon the palm of the glove body. Each of said members is constructed of a strip of rubber of appropriate thickness and the outer as well as the inner 65 end of said members is feathered as at 14, 15 respectively, as shown in Figure 2. The section 28 has a rounded outer end 30 and the section 29 has a tapered or pointed inner end 31. The members taper from their 70 inner towards their outer ends. The opposed ends of the sections of each of said members are straight, as illustrated as 32 and are arranged in close proximity to each other.

75 Vulcanized to the working or gripping surface of the thumb stall 22 is a reinforcing member 33 formed of a strip of rubber of appropriate thickness and which extends from a point in proximity to the outer end 80 of the stall 22 to and projects slightly upon the palm of the glove body. The outer end of the member 33 is rounded as at 34 and its inner end tapered or pointed as at 35. The member 33 has feathered end edges in 85 a manner as illustrated in connection with the reinforcing member shown in Figure 2. The member 33 tapers from its inner towards its outer end.

90 The individual reinforcing members permit of free use of the hand and fingers, do not interfere with the pliability of the glove body and offer no resistance to the closing of the hand when gripping an article. As the reinforcing members are vulcanized onto the glove body and not impregnated throughout the fabric body of the glove, perspiration is prevented thereby increasing the efficiency of the hand covering. The reinforcing members are so placed as 95 to afford greater ease, comfort and wear and further protect the parts of the glove receiving the hardest wear. If desired the rubber reinforcing members can be colored.

100 It is thought the many advantages of a reinforced hand covering, such as a glove in accordance with this invention, can be 105 readily understood, and although the preferred embodiment of the invention is as illustrated and described, yet it is to be un- 110

derstood that changes in details of construction can be had which will fall within the scope of the invention as claimed.

What I claim is:—

- 5 1. A hand covering comprising a body portion in the form of a glove provided with finger and thumb stalls, a resilient reinforcing element of appropriate thickness vulcanized to and extending lengthwise of the front face of each of said finger stalls and formed of a pair of spaced endwise opposed sections, a resilient reinforcing element vulcanized to and extending lengthwise of the front face of said thumb stall, each of said 10 elements having a feathered outer end and a feathered inner end and further having its outer end rounded and its inner end 15 tapered.
- 15 2. A hand covering comprising a body

portion in the form of a glove provided with 20 finger and thumb stalls, a resilient reinforcing element of appropriate thickness vulcanized to and extending lengthwise of the front face of each of said finger stalls and formed of a pair of spaced endwise opposed 25 sections, a resilient reinforcing element vulcanized to and extending lengthwise of the front face of said thumb stall, each of said elements having a feathered outer end and a feathered inner end and further having 30 its outer end rounded and its inner end tapered, the tapered inner end of each of said elements extending slightly upon the palm portion of the glove body.

In testimony whereof, I affix my signature hereto.

PAUL A. JONES.
